DESIGN FOR A LIPSTICK CASE

George Flaxman, Brooklyn, N. Y.

Application December 17, 1946, Serial No. 135,570

Term of patent 3½ years

(Cl. D86—10)

To all whom it may concern:

Be it known that I, George Flaxman, a citizen of the United States, residing at Brooklyn, New York, in the county of Kings and State of New York, have invented a new, original, and ornamental Design for a Lipstick Case, of which the following is a specification, reference being had to the accompanying drawing, forming a part thereof:

In the drawing:

Fig. 1 is a perspective view of a lipstick case showing my new design;

Fig. 2 is a perspective view thereof in open position;

Fig. 3 is a top plan view of Fig. 1; and

Fig. 4 is a bottom plan view of the same.

I claim:

The ornamental design for a lipstick case, as shown.

GEORGE FLAXMAN.
